United States Patent Office.

ISAAC C. TATE, OF NEW LONDON, CONNECTICUT.

Letters Patent No. 78,157, dated May 19, 1868.

IMPROVEMENT IN BRACES FOR BITS.

The Schedule referred to in these Letters Patent and making part of the same.

TO ALL WHOM IT MAY CONCERN:

Be it known that I, ISAAC C. TATE, of New London, in the county of New London, and State of Connecticut, have invented a new and improved Bit-Stock; and I do hereby declare that the following is a full, clear, and exact description thereof which will enable others skilled in the art to make and use the same, reference being had to the accompanying drawings, forming part of this specification, in which—

Figure 1 represents a side view of my improved bit-stock.

Figure 2 is an inverted plan view of the same.

Figure 3 is a detail vertical sectional view of the same, the plane of section being indicated by the line *xx*, fig. 1.

Similar letters of reference indicate corresponding parts.

This invention relates to a new manner of arranging a bit-stock, which will not only be adapted to hold any-sized shank, but which is also adapted to gripe both the square shank and the round body of a bit-stock, whatever their relative thickness may be.

The invention consists in securing to each arm of a brace which has a slotted socket, a spring-jaw, which is to clamp the round portion of the bit, and on which the shoulder for sustaining the head or shank of the bit is formed.

These jaws are made of cast steel, so that the shoulders cannot be easily worn out. It will be seen that when the shank of the bit is, by means of a thumb-screw, fixed in the two arms of the brace, the aforesaid jaws will fit around and clamp the round part of the shank.

A represents the arm of a brace. The same is slotted, so that its socket, *B*, will be divided into two parts, as shown, which may be forced together by a thumb-screw, *a*, if desired. One of the two arms *B* may be hinged or otherwise connected with the arm *A*, or it may be cast in one piece with the same, as may be desired.

On the inside of each arm *B* is a V-shaped recess, *b*, extending from top to bottom of the socket, and broader at the bottom than at the top. No shoulder or stop is formed in these grooves, which are to hold the head or shank of the bit, as is clearly shown in fig. 3.

To the outside of each arm *B* is secured, by means of a screw or rivet, *c*, a spring, *C*, which lies on the side of the arm *B*, as shown.

At the lower end of each spring *C*, below the bottom of the socket *B*, is formed a jaw, *d*. These jaws are so formed that when they are closed together a round hole will be formed between them, which gradually enlarges at the top, (as in fig. 3,) so as to form a hold for the round part of the bit, and a support for the shank of the same.

When the bit is to be inserted, the arms *B* are spread apart, the springs *C* following the same. The head of the bit is then inserted into the groove *b*, and the arms are then closed around it by the use of the screw *a*; thereby the jaws *d* are brought together, and will, by the springs *C*, be firmly clamped around the round part of the bit, as is clearly shown in fig. 3.

It will be seen that the springs *C* will force the jaws *d* against the bit, whatever the size of the head of the bit may be; and as the jaws *d* are formed of cast or other steel, the shoulder formed in them for the support of the head of the bit will not wear out so quick and so easy as the shoulder generally formed in the socket, which is made of malleable iron.

I disclaim the use of a slotted brace socket, whether the parts are hinged together or otherwise connected. I am aware of the patent granted to N. Spofford, and dated November 1, 1859; but as this forms no part of my invention, I do not therefore claim it; but

I do claim, and desire to secure by Letters Patent—

The combination of the spring-jaws *C* with the socket of the bit-stock, substantially as herein shown and described.

I. C. TATE.
